REVERSIBLE GARMENT

Samuel Stark, Brooklyn, N. Y.

Application January 9, 1958, Serial No. 707,927

8 Claims. (Cl. 128—159)

This invention relates to wearing apparel and, more particularly, to swimming trunks and shorts for men and to related items of wearing apparel for women.

It is an object of the present invention to provide reversible garments for men and women having a self-contained integral supporter.

Another object of the present invention is to provide reversible trunks or shorts of the type described, which has a pair of outer covers of different color or design and a single supporter which may be readily worn with either outer covering exposed, as may be desired.

Still another object of the present invention is to provide reversible trunks or shorts having a common waistband and drawstring which may be used to adjust the size of the waist receiving opening with either side of the trunks or shorts exposed and without exposing the constructional features of the garment.

Still a further object of the present invention is to provide reversible trunks or shorts of this type which may be equally as well worn with either side exposed so that a completely finished, neat and tailored appearance may be had at all times.

An additional object of the present invention is to provide a reversible trunk or short construction with a built-in reversible supporter that may be readily applied to the manufacture of swimming trunks, walking shorts, athletic shorts, and other related garments either with or without a fly front.

A practical object of the present invention is to provide a reversible garment of the above type which can be manufactured in large quantities at relatively low cost so as to be made available in various price ranges for general consumption.

All of the foregoing and still further objects and advantages of this invention will become apparent from a study of the following specification, taken in connection with the accompanying drawing, wherein:

Figure 1 is a front elevational view of a garment made in accordance with the present invention in an extended position;

Figure 2 is a front elevational view of the garment shown in Figure 1 in a first intermediate position;

Figure 3 is a view similar to Figure 2, showing the garment in a second or reversed intermediate position;

Figure 4 is an enlarged transverse cross-sectional view taken along line 4—4 of Figure 2;

Figure 5 is a fragmentary view of the garment in the condition ready to wear;

Figure 6 is a fragmentary view of a modification of Figure 4; and

Figure 7 is a view similar to Figure 1, showing a modified form of construction.

Referring now more in detail to the drawing, and particularly to Figures 1 to 5 thereof, a pair of trunks 10 made in accordance with one form of the present invention is shown to include a main body portion 12 and a support 13 made of a material suitable for such sup-

2

port. The main body portion 12 includes a pair of outer coverings 15a and 15b which are identical except for color or design and which are secured together along the peripheral edges thereof, such as by stitching 22. This stitching also serves to secure support 13 between the edges as is shown in Figure 4. However, support 13 may also be secured to either one of the outer coverings by a stitching 50 as is shown in Figure 6. The outer covers have common peripheral portions defining a single common waist receiving opening at one end and a pair of common leg receiving openings at the opposite end. A waist band 17 which preferably includes an elastic strip insert 18 and spaced parallel rows of stitches 19, provides sufficient elasticity to support the garment in the proper position.

The part of the main body portion 12 lying between the waistband 17 and the waist receiving peripheral opening is in the form of a tubular extension 16a and 16b defining a common loop 24 through which a drawstring 25 extends. This drawstring may be provided with a knot 29 in a conventional manner for adjusting the size of the waistband to produce a desired fit. However, each of the outer coverings 15a and 15b and the support 13 is provided with aligned openings 27a, 27b and 28 respectively, for receiving the knot 29 of the drawstring therethrough, for purposes hereinafter described. Instead of a single drawstring, a divided drawstring may be provided.

In wearing this garment, it is possible to reverse the position of the parts so as to expose either of the outer coverings 15a and 15b to view. This is done merely by drawing the support 13 through one of the leg openings and then returning the support into the interior of the garment. Thus, by drawing the support 13 outwardly through one of the leg receiving openings of the garment 10b shown in Figure 3, wherein the one outer covering 15b is exposed, the parts will assume the position shown in Figure 1. By then pushing the support 13 into the interior of the main body portion 12, the adjusted garment 10a, as shown in Figure 2, will have the other outer covering 15a exposed and ready for use. The knot 29 is pulled through the hole 27a and 27b in the outer covering 15a, 15b which is closest to the skin of the wearer and through the hole 28 in the support, as is clearly shown in Figure 4. By then folding the tubular extension part 16a, 16b of the garment inwardly into the main body portion 12 up to the level of the uppermost row of stitches 20 of the waistband 17, this extension is concealed and only the waistband portion 17 of the garment and everything therebeneath is exposed to view, as is shown in Figure 5. It will be noted that all exposed seams of the garment are smooth so as to provide a completely finished appearance.

Referring now to Figure 7 of the drawing, a modified form of construction 30 is shown wherein the main body portion 32 includes a pair of outer coverings 35, each of which has a wide double waistband and is provided with a fly front. The support 33 is secured to the main body portion 32 in a manner similar to that hereinbefore described. However, the front portion of the support 33 is provided with a cutout 42 in the vicinity of the fly front and waistband 37. With the support assembled within the main body portion, the waistband is foldable inwardly about a medial fold line 45 to produce a finished appearance. The waistband has a releasable closure flap 39 and associated snap type or other similar buttons 40a and 40b on both of the outer coverings forming the main body portion. Thus, the slide fastener or similar closure 43 and adjustable flap 39 may be opened and closed at will with the enlarged cutout 42 intermediate the leg cutouts 34 permitting proper functioning of the garment.

It will be recognized that this construction may be

applied to substantially any type of related garment in which it is desired to attain the reversible feature described while providing a completely finished and tailored appearance in either of the selected positions.

While this invention has been described with particular reference to the constructions shown in the drawing, it is to be understood that such is not to be construed as imparting limitations upon the invention, which is best defined by the claims appended hereto.

Having thus described my invention, I claim as new and desire to secure by Letters Patent:

1. Reversible garment of the kind described comprising, in combination, a reversible main body portion and a support, said main body portion including a first outer cover and a second outer cover, said first and second outer covers being peripherally connected together to define a common waist opening and a pair of common leg openings, each of said covers being extended beyond said waist opening to form a protruding tubular portion and said support being secured at the free peripheral edges of the covers forming the tubular portion.

2. Reversible garment of the kind described comprising, in combination, a reversible main body portion and a support, said main body portion including a first outer cover and a second outer cover, said first and second outer covers being at least peripherally connected together for simultaneous movement between selective reversed positions, said connected outer covers having connected peripheral portions defining a single common waist receiving opening and a pair of common leg receiving openings, said support having portions defining a waist receiving opening and a pair of leg receiving openings, each of said covers being extended beyond said waist opening defined by the covers to form a protruding tubular portion and said support being secured at the free peripheral edges of the two covers forming said tubular portion.

3. Reversible garment of the kind described, comprising, in combination, a reversible main body portion and a support, said main body portion including a first outer cover and a second outer cover, said outer covers being at least peripherally connected together for movement between selective reversed positions, said connected outer

covers having connected peripheral portions defining a single common waist receiving opening and a pair of common leg receiving openings, cover portions intermediate said waist receiving opening and said leg receiving openings defining a waistband, said support having portions defining a waist receiving opening and a pair of leg receiving openings, each of said intermediate cover portions being extended beyond the waistband to form a protruding tubular portion and said support being secured at the free peripheral edges of the two covers forming said tubular portion, said tubular portion together with the support thereto being foldable inwardly into said main body portion in either selected position of reversal.

4. Reversible garment as set forth in claim 3, wherein a drawstring extends through said tubular portion for adjusting the diametrical width of said common waist receiving opening.

5. Reversible garment as set forth in claim 4, wherein the ends of said drawstring are adjustably formed into a knot, a knot receiving opening in said tubular portion extending from each of said outer covers and in said support in registry with each other when the tubular portion is folded inwardly for releasably receiving said knot therethrough from within the interior of said tubular portion.

6. Reversible garment as set forth in claim 5, wherein said outer covers are secured together by common stitching at said common waist opening.

7. Reversible garment as set forth in claim 3, wherein said intermediate cover portions comprise a releasable waistband flap, and said main body portion includes a fly front extending from said flap toward the leg openings.

8. Reversible garment as set forth in claim 7, wherein said support defines a cutout in the vicinity of said fly front and said releasable flap of said intermediate cover portions.
